FIG. 2

FIG. 3

FIG. 1 is a front perspective view of a lathe embodying our new design;

FIG. 2 is a front perspective view thereof taken from the end opposite that shown in FIG. 1; and

FIG. 3 is a rear view, partially in perspective.

Our new and novel design is substantially that shown in full lines, with the parts shown in dot-dash lines being for illustrative purposes.

What we claim is:

The ornamental design for a lathe, substantially as shown and described.
